UNITED STATES PATENT OFFICE.

CARSON F. HOWES, OF HUDSON, MASSACHUSETTS.

TICKET-HOLDER.

SPECIFICATION forming part of Letters Patent No. 725,711, dated April 21, 1903.

Application filed July 30, 1902. Serial No. 117,708. (No model.)

To all whom it may concern:

Be it known that I, CARSON F. HOWES, a citizen of the United States, residing at Hudson, in the county of Middlesex and State of Massachusetts, have invented certain new and useful Improvements in Ticket-Holders; and I do hereby declare the following to be a full, clear, and exact description of the invention, such as will enable others skilled in the art to which it appertains to make and use the same.

This invention relates to ticket-holders; and it consists in the novel construction and combination of the parts hereinafter fully described and claimed.

15 In the drawings, Figure 1 is a front view of the ticket-holder. Fig. 2 is a side view of the same. Fig. 3 is a cross-section taken on the line $x-x$ in Fig. 1.

20 A is a head or button, of india-rubber or other elastic material, provided with a slit or notch b extending crosswise through it for the greater part of its depth. The base of the head A is rounded, so that protuberances c are formed one on each side of the slit b .

25 B is a staple which is passed through the head A at the bottom of the slit b . The staple is inserted in the seat of a railroad-carriage, and when driven in tightly it springs the edges of the slit toward each other, so that they 30 grip a ticket when the same is thrust into the slit.

C is a base-washer provided with protuberances d , which come under the protuberances

c . The base-washer may be omitted altogether, if desired, or its protuberances d may 35 be omitted, or the protuberances c on the head A may be omitted when the washer is provided with protuberances.

What I claim is—

1. In a ticket-holder, the combination, with 40 a head of elastic material having a slit in it, of a staple inserted through the said head at the bottom of its said slit, substantially as set forth.

2. In a ticket-holder, the combination, with 45 a head of elastic material having a slit in it, of a staple inserted through the said head at the bottom of its said slit, and protuberances under the head one on each side of its slit for contracting the slit when the staple is driven 50 into a support, substantially as set forth.

3. In a ticket-holder, the combination, with 55 a head of elastic material having a slit in it, of a staple inserted through the said head at the bottom of the slit, a base-washer, and protuberances between the said head and washer on each side of the said slit, said slit being contracted when the staple is driven into a support, substantially as set forth.

In testimony whereof I affix my signature 60 in presence of two witnesses.

CARSON F. HOWES.
